UNITED STATES PATENT OFFICE.

JOHN W. SNIDER, OF FAIRLAND, INDIANA.

BREEDING-CALENDAR.

SPECIFICATION forming part of Letters Patent No. 351,131, dated October 19, 1886.

Application filed July 2, 1886. Serial No. 206,933. (No model.)

To all whom it may concern:

Be it known that I, JOHN W. SNIDER, of Fairland, in the county of Shelby and State of Indiana, have invented a new and Improved 5 Breeding-Calendar, of which the following is a full, clear, and exact description.

The object of the invention is to furnish a calendar having attached adjustable disks for indicating the period of parturition or time 10 to young will or should be brought forth, the date of copulation or conception being known.

The invention is applicable to animals of all kinds, also to the hatching of the eggs of poultry or birds of different kinds, &c.; and it consists in a calendar of novel description, including certain constructions and combinations of parts, substantially as herein shown and described, and whereby the calendar may not only be used as a changeable or perpetual 15 20 one for ordinary reference purposes, but as a special one for breeding purposes, as above described.

Reference is to be had to the accompanying drawings, forming part of this specification, in 25 which similar letters of reference indicate corresponding parts in all the figures.

Figure 1 represents a partly-broken front or face view of a calendar having my invention applied. Fig. 2 is a rear view of the same, 30 and Fig. 3 a longitudinal section thereof upon the line *x*-*x* in Fig. 1.

A indicates the main body, which may be composed of an oblong piece of card-board or other suitable material with an aperture, *b*, in 35 it at or near its one end, or otherwise suitably disposed. Down or along one side of the face of the body *A* are two tables or strips, *B*, *C*, the one of which, *B*, that is fixed has the names or abbreviations of the days of the week extending over a period of five weeks and two 40 days printed or otherwise exposed in succession upon it. The other of said strips, *C*, that is arranged along the side of the fixed strip *B*, has the number of days (thirty-one) in the longest months of the year exhibited in succession from 1 to 31 upon it. The last strip, *C*, is made capable of being slid up and down, as through staples *c* or other suitable fastenings, which may also serve to hold both strips to 45 50 their places. By means of the sliding of strip *C*, which is a date one, it may be adjusted in such

variable relation to the indications on the fixed strip *B* as to give the day of the week upon which the first or any particular date of any month falls in any year. To aid the setting of 55 this strip *C* a table, *D*, showing the first of the month for twelve months during one or more years, may be secured on the face of the body *A*. The names of months are exposable in succession by suitably turning an adjustable 60 or rotatable disk, *E*, having the several months of the year arranged in succession at equal distances apart around the marginal portion of its face, so as to exhibit the month through the aperture *b* in the body. This may be said 65 to complete the calendar for general use, and is also serviceable for indicating dates or days of the week in any particular month of any year when a breeding record or calculation has to be made. 70

To adapt the calendar for use in connection with the breeding of stock, I elect to use two rotatable monthly calendars or disks, though for a single stock a single disk having two circular rows of months, the one expressing the 75 period of copulation or conception and the other the period of parturition or birth, substantially as hereinafter described for two disks, might be used.

The disk or monthly calendar *E* forms one 80 of the pair of disks and a smaller disk, *F*, the other one of said pair. The disk *F*, which is arranged upon the face of the disk *E*, has the several months of the year disposed on and around its face, as in the case of the disk *E*, 85 so that it also forms a monthly calendar. These two disks are concentric in relation with each other and are fitted to turn both independently and collectively upon a single eyelet, rivet, or pivot, *d*, which secures them upon the back of 90 the body *A*. Said disks are or may be made of card-board or any suitable material, and the rearmost disk, *E*, be clamped by bending over a portion, *e*, of the body *A* cut, but not removed, when making the aperture *b*; but this 95 clamp or clip *e* does not prevent the rotary movement of the disk *E*.

The names of the months, or abbreviations thereof upon the face of the disk *F*, are covered from exposure through the aperture *b*, 100 when required, by a movable screen or blind, *G*, which may be pivoted on the face of the

body A at the same center as the disks E and F. By turning the blind or shutter to one side, as shown in Fig. 1, then some one of the series of monthly indications upon the face of the disk F is exposed in common with a monthly indication upon the disk E through the aperture b.

The disk E has apertures f in it arranged in radial relation to the months marked upon the face of said disk and within the range or diameter of the disk F, and opposite these slots or apertures f are printed or inscribed the names of the different animals, &c., it is required to use the breeding calendar for. Upon the back of the disk F is a stud or pin, g, which, by a suitable circular adjustment of the disks and flat position of the disk E upon the disk F, is free to engage with some one of the apertures f in the disk E, whereby the rotation of the two disks in common is practicable; but upon slightly raising the marginal portion of the disk E opposite the clamp e, which is readily done by constructing the disk E of suitable flexible or elastic material—such as card-board—then the pin g may be disengaged from the aperture f it was entered within, and the two disks E and F be at liberty to be independently rotated or adjusted, or the disk E only be rotated, while the disk F remains stationary. A convenient means for thus engaging and disengaging the two disks consists in a simple slide, H, formed of a strip of metal or piece of wire bent upon itself, with a fork, i, at its inner end and having a wedge-shaped projection, k, at the root of the fork. This slide is arranged on back of the body A, over a lower strip, I, of card-board or other suitable material fastened on the body A, but left free at its upper end to overlap the lower marginal portion of the disk F. Said slide H is made capable of being moved up or down through staples or guides l, which staples or guides secure the slide to or on the back of the body A or strip I thereon.

Supposing the disks E and F to be engaged with one another, as described, and the pin g to be in an aperture, f, directly over and in line with the slide H, as shown in Fig. 2, then by pushing the slide inward or upward the projection k on said slide will lift the disk E from engagement with the pin g of the disk F, and the fork i will straddle the pin g, to hold the disk F stationary, while the disk E is turned or set for any particular kind of stock, as indicated by the inscriptions on the back of said disk opposite the apertures f. Upon drawing down or back the slide H the pin g will be entered within the aperture f, brought in position for the purpose as described, and the two disks E and F will be engaged with one another by the return flexing action of the disk E as the projection k is moved from under H, and the fork i will be relieved from its hold of the disk F by its pin g, and the two disks be free to rotate in common again—as, for instance, by applying the finger to the mar-

ginal portion of the disk E, opposite a cut-away portion, m, in the side of the body A.

The strip I, while it does not restrain the rotary movement of the disk F, serves as a 70 guide for the slide H when moving the slide inward to lift the disk E, and to engage it by its fork with the pin g, and prevents said slide, when thus moved, from catching against or passing under the disk F. 75

The larger disk, E, is the one used for indicating the period of copulation or supposed conception, and the smaller disk, F, the one for showing the probable or approximate period of parturition or birth. These disks may 80 only give the periods of gestation in months for different kinds of stock, and the exact date may be ascertained by adding or subtracting a certain number of days, as shown by a table, M, to or from the intervals shown in 85 months upon the faces of the disks E and F, through the exposing-aperture b in the body. A table of exact periods of gestation for the different stock to which the calendar is here shown applied is represented at N on the back 90 of the body A.

The inscriptions on the back of the disk E of the different kinds of stock, opposite the apertures f, are so arranged that whenever the engaging pin g is entered within the aperture f opposite a certain kind of stock, and the two disks turned in common to expose through the opening b the month of copulation or conception on the larger disk, the month or period of parturition or birth will be shown immediately 95 beneath it upon the face of the disk F—that is, when the blind or shutter G is turned to one side to expose it. Thus, to use the calendar for breeding purposes, the blind G is turned aside to allow the months of both disks 100 to show at the aperture b. The two disks E and F, being engaged, are then turned till the slot or aperture f, with the pin g in it, is opposite the slide H. Said slide is then pushed in till the disks are separated, after which the disk E is turned till the aperture f, indicative of the particular stock it is desired to expose on the calendar, is over the pin g of the disk F, held by the fork of the slide. The slide H is then drawn down or out, and the two disks, 110 which then become engaged again, are turned in concert till the month of copulation on the disk E is exposed through the aperture b, when the period or month of parturition shown on the face of the disk F will also be exposed 115 through the aperture b. 120

If, for instance, the calendar is set for horse-breeding, which is the illustration shown in the drawings, and supposing copulation to have taken place in February, then that month will 125 be exposed on the disk E, and January on the disk F, a period of eleven months, which is the number of months for gestation of a mare, will be exposed on the disk F; or the engaged disks may be turned to expose on the disk E 130 a different month of copulation, when the period of parturition, showing eleven months

later, will be exposed on the disk F. A like action takes place when using the calendar for the other kinds of stock, only the period of gestation being changed as exhibited on the 5 faces of the engaged disks where exposed at the opening b in the body. When an exact date is required, then the number of days opposite a particular stock, as shown on the table M, for instance, should be added to or 10 subtracted from the date of copulation or conception during the month shown on the disk E, and for fixing these dates, both by numbers and the day of the week, the tables or strips B C will be found convenient to refer to; 15 or the blind G may closed over the exposed portion of the disk F through the aperture b, and the disk E be used in connection with the tables B C for general reference, or for any purpose to which a calendar is applicable, as 20 hereinbefore explained.

It should here be understood that while for the convenience of description the strip or table B of weeks and days is herein referred to as the fixed one, and the strip or table C of 25 dates as the sliding or adjustable one, the order of the same may be reversed—that is to say, the table B may be the movable one and the table C the fixed one. Such change would not affect the result nor the manner in which 30 it is obtained, and I consider such change of said strips or tables as the equivalent of making the table B stationary and table C adjustable, as herein described.

Having thus described my invention, I claim 35 as new and desire to secure by Letters Patent—
1. In a calendar for indicating the periods of parturition or birth of stock, the date of supposed conception being known, the combination of a rotatable monthly calendar or disk 40 having the names of the stock opposite the months marked upon it, a second rotatable monthly calendar or disk expressive of the periods of parturition, and means for engaging and disengaging said disks, and adapted to engage 45 them at different points in their monthly

divisions, essentially as and for the purposes herein set forth.

2. In a stock-breeding calendar, the combination, with the body A, of the calendar having an exposing-aperture, b, of the rotatable 50 monthly calendar or disk E, having the names of the stock opposite the months marked upon it, the smaller concentric rotatable monthly calendar or disk, F, and means for disengaging said disks from each other, and adapted to engage them at different points in their monthly 55 divisions, substantially as specified.

3. In a stock-breeding calendar, the rotatable monthly calendar or disk E, having apertures f, and the names of the stock opposite 60 the months marked upon it, in combination with the lesser and concentric rotatable monthly calendar or disk F, provided with an engaging pin or stud, g, essentially as described.

4. In a stock-breeding calendar, the combination, with the rotatable monthly calendar or disk E, having apertures f, and the names of the stock opposite the months marked upon it, and the lesser and concentric rotatable monthly calendar or disk F, provided with an 65 engaging pin or stud, g, of the slide H, adapted to lift the disk E from engagement with the disk F and to hold the latter from turning, substantially as and for the purposes specified.

5. In a stock-breeding calendar, the combination, with the body A, having an exposing-aperture, b, of the rotatable monthly calendar or disk E, having the names of the stock opposite the months marked upon it, the second 75 rotatable monthly calendar or disk, F, adapted 80 to engage with the disk E at different points in the monthly divisions on it, the adjustable blind or screen G, the fixed table B of weeks and days, and the sliding or adjustable table C of dates, substantially as shown and described. 85
